Harry Smith

UNITED STATES PATENT OFFICE.

LOUIS N. D. WILLIAMS, OF OGONTZ, PENNSYLVANIA.

FACILITATING MECHANICAL TRANSFER OF STITCHES FROM THE NEEDLES OF KNITTING-MACHINES.

1,308,828.

Specification of Letters Patent.

Patented July 8, 1919.

Application filed February 15, 1917. Serial No. 148,755.

To all whom it may concern:

Be it known that I, LOUIS N. D. WILLIAMS, a citizen of the United States, residing in Ogontz, Pennsylvania, have invented certain

5 Improvements in Facilitating Mechanical Transfer of Stitches from the Needles of Knitting-Machines, of which the following is a specification.

The object of my invention is to facilitate 10 the mechanical transfer of the stitches from the needles of a knitting machine after the completion of a toe pocket or other fashioned web thereon by reciprocating knitting.

In the accompanying drawing 15 Figure 1 is a perspective view of the toe end of a stocking blank of the type to which my invention relates before the stitches around the upper edge of the toe pocket have been united to those around the instep portion of the foot web, and

20 Fig. 2 is a diagrammatic view showing, by full lines, the stitches around the mouth of the toe pocket as produced in the ordinary manner, and, by dotted lines, my addition thereto.

25 In knitting so-called "seamless" stockings the needles around one-half of the cylinder of the machine are, upon the completion of the foot web, put out of action but permitted 30 to retain their stitches and the production of the toe pocket by reciprocating knitting upon the needles around the other half of the machine is then proceeded with, needle after needle first at one end and then at 35 the opposite end of the set being successively put out of action but permitted to retain its stitch until the web has been narrowed to the desired extent, and these needles being then successively restored to action in 40 reverse order so as to gradually widen the web again, and unite the stitches at the edges of the widened web to those at the edges of the narrowed web.

45 Where the direction of travel of the knitting yarn is reversed in reciprocating knitting, however, it forms a selvage stitch at the end of said course, with the result that when the final course is completed such selvage stitch is carried by the needle at

one end of the semi-circular set upon which 50 the toe pocket was knitted.

In Fig. 2 of the drawing, 1 represents this selvage stitch of the final course, 2 the stitches at the front end of the sole portion of the foot web, in continuation of which 55 the toe pocket was knitted, and 3 the stitches at the front end of the instep portion of the foot web.

As will be seen in Fig. 2, both of the 60 sinker wales of the selvage stitch 1 of the final course are drawn in the same direction through the engaging loop of the previous course, consequently, when this stitch is produced, both sides of it are caused to cling 65 closely to the needle which produces it and, as a result, the stitch hugs the needle so tightly that it is difficult if not impossible to properly introduce a transfer point into the stitch for the purpose of removing it 70 from the needle.

This objection it is the aim of my invention to overcome, and in doing so I proceed in the following manner:

75 After the completion of the toe pocket upon the needles around one half of the machine I put into action the needles around the other half of the machine which carry the stitches 3 around the front end of the instep portion of the foot web and then 80 form one or more complete courses of "full" 80 stitches (as distinguished from "selvage" 85 stitches) upon all of the needles of the machine. In Fig. 2 one such course of full stitches is shown at 4. The stitches upon all 85 of the needles are therefore alike and no difficulty will be experienced in inserting the transfer points 5 into any of the stitches.

90 After one half of the stitches 4 have, by means of the transfer points, been doubled with the remaining half of the same, said 90 stitches may be united as usual by means of a separately produced course of stitches, so as to close the toe of the stocking.

95 Although I have shown and described my invention as applied to the terminal stitches of the fashioned toe pocket of a stocking, it may, as will be evident, be applied to the reciprocated terminal course of any web,

either in a stocking or other garment, which web has to be transferred by mechanical means.

I claim:

- 5 The mode herein described of preparing for transfer the edge of a knitted web produced partly by circular knitting and partly by reciprocating knitting, said mode consist-

ing of adding thereto a complete course of stitches produced by circular knitting, which 10 stitches are adapted for the reception of transfer points.

In testimony whereof I have signed my name to this specification.

LOUIS N. D. WILLIAMS.
